[57] CLAIM

The ornamental design for a multi-position arm chair, as shown and described.

DESCRIPTION

FIG. 1 is a top, front and side perspective view of a multi-position arm chair showing my new design;

FIG. 2 is a front perspective view thereof;

FIG. 3 is a side perspective view thereof, the side opposite that shown in FIG. 3 being the mirror image thereof;

FIG. 4 is a top perspective view thereof; and

FIG. 5 is a rear perspective view thereof.

FIG. 4

FIG. 5
